UNITED STATES PATENT OFFICE.

PETER EVERET PETERSON, OF BUTTE, MONTANA.

ORE-REDUCING FURNACE.

1,051,512.

Specification of Letters Patent. Patented Jan. 28, 1913.

Application filed May 10, 1912. Serial No. 696,491.

To all whom it may concern:

Be it known that I, PETER EVERET PETERSON, a citizen of the United States, residing at the city of Butte, in the county of Silverbow and State of Montana, have invented certain new and useful Improvements in Ore-Reducing Furnaces, of which the following is a specification.

My present invention pertains to an improved furnace for the reduction of ores, and more particularly for the reduction of zinc ores, one embodiment thereof being illustrated in the annexed drawings, wherein:

Figure 1 is a perspective view of the furnace; Fig. 2 a longitudinal sectional view; Fig. 3 a transverse vertical sectional view, taken on the line III—III of Fig. 2; and Fig. 4 a similar view on the line IV—IV.

The main object of my invention is to construct an apparatus which will condense the vapors, so as to produce pure metal, means being provided whereby the flow of the cooling medium (air) about the condensing tubes may be so regulated as to accomplish the desired result. Thus, for instance, in the treatment of zinc ores, the condenser will act upon the vapors so as to produce metallic zinc, and prevent the formation of blue powder or zinc dust.

Stated broadly, the condenser may be said to comprise a series of condensing ducts through which the vapor passes, combined with means for causing a current of air to be passed about and around the same, the air and vapor passing in the same general direction, so that the hottest portion of the vapor is subjected to the cooling medium while the latter is at its lowest temperature. Moreover, the general direction of movement of the vapor through the condenser should be downward toward the spelter-collecting chamber, the hot spelter modifying and assisting the action of the condenser.

A simple and effective arrangement of an apparatus for carrying out my invention is illustrated in the annexed drawings, where-

1 denotes the smelting retort in which the material under treatment is vaporized by an electric current passing between the electrode 2 situated in the base of the retort, and an electrode 3 extending through a cover-block 4. Electrode 3 is made hollow and material is preferably introduced therethrough. It is to be understood that any

form of heating apparatus may be employed, that shown being merely illustrative.

The condenser is located to one side of the retort, the upper vapor-receiving chamber 5 opening at one end, at 6, into the upper portion of the retort. Said chamber is in communication with the upper ends of the condensing tubes 7, which extend downwardly and open into the spelter-receiving chamber 8. The tubes pass through a windbox or chest 9, the exterior of the tubes being exposed throughout substantially their entire length.

Openings 10 are formed in the upper portion of the chest upon each side thereof, and air trunks 11 and 11^a are in communication therewith, air being supplied to said trunks from a blower or blowers. Vents 12 are formed in the lower portion of the box or chest through which the air may escape. Suitable dampers, as 13, will be provided for controlling the flow of air through the box or chest.

The fumes and such vapors as are not condensed, pass from the spelter chamber 8 through ports or openings 14, into ducts 15, through which they are carried away.

The spelter may be withdrawn from the spelter-collecting and receiving chamber through a tap opening 16, while access may be had to the tubes and chamber 5 through openings formed in the top and end wall of the condenser, which openings will be closed by suitable closures 17 and 18. Any desired form of clean-out door may be provided for the chamber 8.

While the tubes have been shown as occupying a vertical position, it is not essential that they should be so arranged; they may be inclined, and so long as they extend downwardly they may be said to fall within the scope of the present invention.

In operation the vapors pass from the retort into the upper chamber 5, thence pass downwardly through the tubes, air at the same time being forced into the air-box, entering the upper part through openings 10 and impinging directly upon the upper portions of the tubes, which parts are the hottest. Thus the vapors while in their hottest state are brought into contact with that portion of the tubes which are subjected to the coolest air. The vapors pass downwardly in the tubes and the cooling air likewise passes downwardly in contact with the outer

- portions of the tubes, finally passing out of the trunk or chest through openings 12. The temperature of the tubes is thereby regulated and controlled so that the vapors 5 are condensed and the spelter or metallic zinc gathers in the spelter chamber 8, from whence it is withdrawn from time to time. The cooling medium and the vapors thus travel in the same general direction, an arrangement which has proven highly effective. The collection of the hot spelter in the chamber beneath the discharge end of the tubes likewise assist in the proper operation 10 of the condenser.
- 15 Having thus described my invention, what I claim is:
1. In a condenser, the combination of a plurality of passages in communication with the exit of a retort, said passages extending 20 in a downward direction; and means for applying a cooling medium to the exterior of said passages, said medium passing in the same general direction about said passages as the vapors which pass therethrough, whereby the hottest portion of the passages will be subjected to the cooling medium while the latter is at its lowest temperature.
  2. A condenser, comprising in combination a chamber opening into the upper portion of a retort and adapted to receive vapors therefrom; a plurality of tubes extending downwardly from said chamber; a spelter chamber located beneath said tubes; and means for causing a current of air to flow 30 around said tubes in a downward direction, whereby the upper portion of the tubes into which the hot vapors are introduced

will be subjected to the influence of the coolest air.

3. A condenser, comprising in combination a chamber in communication with a retort and adapted to receive the vapors passing therefrom; an air-box or chest located below said chamber; a series of tubes extending downwardly from said chamber and through the chest; a spelter-receiving chamber located beneath said tubes and into which they discharge; means for forcing air into the upper portion of the chest and into contact with the upper portion of the tubes; exit 40 45 openings located in the lower portion of said chest through which the air may escape; and fume conduits extending from the spelter-receiving chamber.

4. A condenser, comprising in combination a downwardly-extending passage or conduit communicating at its upper end with a retort from which it receives the vapors to be condensed; a spelter chamber into which said conduit discharges; and means for applying a cooling medium to the exterior of said conduit, said medium while coolest first contacting with the uppermost portion of the conduit and thence passing in the same general direction about the exterior of said conduit as the vapors take in 50 55 passing through said conduit.

In testimony whereof I have signed my name to this specification in the presence of two subscribing witnesses.

PETER EVERET PETERSON.
